METHOD OF MAKING SHOES

Mathias H. Baudendistel, St. Louis, Mo.

Application November 6, 1940, Serial No. 364,482

5 Claims. (Cl. 12—142)

This invention relates to a method of making shoes.

An object of this invention is to produce a shoe of a type which can be economically manufactured and to provide a process for making shoes which will be economical. In particular an object of the invention is to provide a shoe and method of making the same which will eliminate the lasting of the forepart of the shoe.

The invention comprises the elements and steps with their combinations specifically pointed out in the appended claims, while a preferred embodiment of the invention is illustrated in the accompanying drawings and presently described.

Fig. 1 is a perspective view of a shoe made by and embodying the present invention;

Fig. 2 illustrates one step in the process and shows a midsole with a vamp strip attached thereto;

Fig. 3 shows a closed shoe upper complementary to the assembly shown in Fig. 2;

Fig. 4 is an inverted plan view of the shoe before the outsole is attached;

Fig. 5 is a section on line 5—5, Fig. 1;

Fig. 6 is a section on line 6—6, Fig. 1; and

Fig. 7 is a perspective view of a modification.

By the present process a shoe is produced without lasting, except at the heel portion. A vamp strip 1 is first secured to a midsole 2 about the forepart of the midsole and then a closed upper is attached to the upper edge of the strip at the forepart of the shoe and the heel portion of the upper is turned or lasted over the edge of the midsole as if it were an insole in a conventional manner. The term midsole is used to designate the sole member 2 although this member performs in part at least the functions of an insole.

As illustrated in the drawings, the midsole 2 has its forepart corresponding, as it may be said, to a conventional outsole pattern while the heel portion conforms to a conventional insole pattern. Fig. 2 shows the completion of the first step in assembling the shoe, that in which the strip 1 forming a part of the upper is attached to the midsole. As specifically shown this attachment is made by a seam 3 with the bottom marginal edge of the strip turned inwardly, the seam being spaced well away from the edge of the midsole.

Fig. 3 shows a closed shoe upper assembled and in condition to be attached to the midsole and strip shown in Fig. 2. This upper has a piece 4 which includes integrally a vamp portion

and quarter portions, the vamp portion being abbreviated however so that the strip 1 completes the upper. The closed upper also has a lining 5 which may extend throughout the entire extent of the portion 4, except at the lower part of the vamp, and also includes a piece 6 which extends below the upper piece 4. This lining extension will cover a portion of the inner surface of the strip 1 when the closed shoe upper has been attached to the strip and midsole, and especially will cover the junction between the end of the strip and the upper. The bottom edge of the extension 6, in the completed shoe, reaches approximately to the bottom of the shoe, as shown in Fig. 5.

After the parts shown in Fig. 2 and Fig. 3 have been completed respectively the closed upper is then attached to the strip 1 by a seam 7. The marginal edge of the heel portion is brought over the edge of the midsole and secured by tacks 8 in a conventional manner. In this operation a last may be used, or merely a heel form may be employed instead. Before lasting the heel portion a fiber reinforcement 9 is preferably inserted and a shank stiffener 10 may be attached. The projecting portion 6 of the lining is cemented to the inner face of the strip 1 and a seam 11 is run to secure the lining to the strip. Preferably this seam is run just below the seam 7 so that in actual practice it is obscure.

After these operations have been completed the shoe is ready for bottoming, and this may be done in any conventional manner. As specifically shown an outsole member 12 is attached by a seam 13 which is run around the exposed marginal portion of the midsole throughout the forepart of the shoe while the heel portion is secured by tacks. In the construction shown in Fig. 1, Fig. 5 and Fig. 6, the outsole member 12 is hard rubber suitable for attaching a crepe rubber sole 14, in a manner which is well known in the art. For the purpose of providing attaching means at the heel, when a rubber sole is to be applied, a heel strip 15 is attached to the shoe and particularly to the sole member 2 by tacks and the outsole member 12 is attached to the strip by a seam 16. This seam, of course, may be a continuation of the seam 13.

Fig. 7 shows a shoe of the same general character as Fig. 1, but with the sole and heel of leather. In this case an outsole 17 is attached to the midsole 2 in part by a seam 18 and in the same manner as previously described in connection with Fig. 1, while a heel 19 is attached in any conventional manner.

A conventional sock liner 20, shown in Figs. 5 and 6, may be inserted after the shoe has been bottomed.

In the construction specifically illustrated the strip 1 is secured to the upper side of the sole member 2. It may be understood, however, that the sole member 2 may be made throughout to the usual insole pattern and that the strip 1 may have its marginal edge stitched to the underside of said sole member, in which case the outsole may be attached by the McKay process, by cementing, or by any one of several other known methods.

Various changes may be made in the details of construction, within the scope of the appended claims, without departing from the spirit of this invention.

I claim:

1. The method of making a shoe comprising securing a separate vamp strip about the forepart of a midsole by stitching an inturned bottom edge of the strip to the midsole, constructing a closed upper with its forepart abbreviated to the extent that it is completed by the addition of the vamp strip, securing said closed upper to the strip by stitching the lower edge of the upper to the upper edge of the strip, turning the margin of the heel portion of the upper over the edge of the heel portion of the midsole, and attaching an outsole to the midsole with the said margin therebetween.

2. A method of making a shoe comprising securing a separate vamp strip about the forepart of a midsole by stitching an inturned bottom edge of the strip to the midsole, constructing a closed upper with its forepart abbreviated to the extent that it is completed by the addition of the vamp strip and having a lining extending below the abbreviated portion in a position to overlap the ends of said strip, securing the closed upper to the strip by stitching the lower edge of the upper to the upper edge of the strip and bringing the margin of the heel portion over the edge of the heel portion of the midsole, fastening the said extended portion of the lining down upon the strip to cover the junction between the end of the strip and the adjacent portion of the upper, and attaching an outsole to the midsole with the said margin therebetween.

3. The method of making a shoe comprising forming a midsole to a conventional outsole pattern except at the heel where it is formed to a conventional insole pattern, securing a separate vamp strip about the forepart of the insole spaced inwardly from the margin of the insole by stitching through the insole and a bottom margin of the strip, securing a closed upper to the strip by stitching the lower edge of the upper to the upper edge of the strip, turning the margin of the heel portion of the upper over the edge of the heel portion of the insole, securing the said margin thereto, and attaching an outsole to the insole, in part by stitching through the outsole and the marginal portion of the insole outwardly from the vamp strip, with the margin of the heel portion of the upper between the insole and the outsole.

4. The method of forming a shoe comprising securing a separate continuous vamp strip entirely about the forepart of a midsole forwardly of the location of the heel breast, by stitching an inturned bottom edge of the strip to the midsole, stitching the bottom edge of a closed upper to the upper edge of the strip, thereby forming the entire shoe except the heel portion without the use of a last, turning the margin of the heel portion of the upper over the edge of the heel portion of the insole, securing the said margin thereto, and attaching an outsole to the insole with the said margin therebetween.

5. The method of forming a shoe comprising securing a separate continuous vamp strip entirely about the forepart of a sole member forwardly of the location of the heel breast by fastening a bottom edge of the strip to said sole member, constructing a closed shoe upper with its forepart abbreviated to the extent that it is completed by the addition of the vamp strip, securing said abbreviated upper to the upper edge of the strip, thereby forming the entire shoe except the heel portion without the use of a last, turning the margin of the heel portion of the upper over the edge of the heel portion of the sole member, securing the said margin thereto, and attaching an outsole to said sole member with the said margin therebetween.

MATHIAS H. BAUDENDISTEL.
